Primary Examiner — Jonathan J Han*Assistant Examiner* — Christen Pilar Brown(74) *Attorney, Agent, or Firm* — Banner & Witcoff, Ltd.(57) **CLAIM**

The ornamental design for a shoe, as shown and described.

DESCRIPTION

FIG. 1 is a front perspective view of a shoe showing my new design; and,

FIG. 2 is a side view thereof.

The remainder of the shoe shown in a greyed out photographic depiction forms no part of the claimed design. The broken line immediately adjacent to the photographic area represents the bounds of the claimed design and forms no part thereof.
